UNITED STATES PATENT OFFICE

142,177

DESIGN FOR A MANICURE APPLIANCE

Freeman R. Walsh, Waltham, Mass.

Application May 18, 1945, Serial No. 119,610

Term of patent 14 years

(Cl. D86—10)

To all whom it may concern:

Be it known that I, Freeman R. Walsh, a citizen of the United States, residing at Waltham, in the county of Middlesex and Commonwealth of Massachusetts, have invented a new, original, and ornamental Design for a Manicure Appliance, of which the following is a specification, reference being had to the accompanying drawing forming a part thereof, in which:

Fig. 1 is a plan view of a manicure appliance showing my new design, and

Fig. 2 is a view in cross section on line 2—2 of Fig. 1.

I claim:

The ornamental design for a manicure appliance, as shown.

FREEMAN R. WALSH.
